UNITED STATES PATENT OFFICE.

JOHN S. RUDZINSKI, OF PERRY, NEW YORK.

LINK-PADLOCK.

1,253,100.

Specification of Letters Patent.

Patented Jan. 8, 1918.

Application filed March 27, 1917. Serial No. 157,636.

To all whom it may concern:

Be it known that I, JOHN S. RUDZINSKI, a citizen of the United States, residing at Perry, in the county of Wyoming and State of New York, have invented certain new and useful Improvements in Link-Padlocks; and I do hereby declare the following to be a full, clear, and exact description of the invention, such as will enable others skilled in the art to which it appertains to make and use the same.

This invention relates to a padlock and has for one of its objects the provision of a novel form of shackle having its ends relatively spaced to permit the insertion of a member, which is to be locked and the space adapted to be closed by means carried by one of the ends of the shackle and adapted to engage the other end.

Another object of this invention is to provide a movable locking barrel upon one end of the shackle and adapted to be moved in engagement with the other end of the shackle to close the space occurring between the ends of the shackle.

A further object of this invention is to provide means for holding the barrel against movement when in a position closing the space occurring between the ends of the shackle.

A further object of this invention is to provide means formed upon the barrel for receiving a key whereby upon insertion of the key, the barrel will be freed from one end of the shackle and permitted to slide thereon for opening the space occurring between the ends of the shackle.

A still further object of this invention is the provision of a link padlock of this character, which shall be simple, durable and efficient, and which may be manufactured and sold at a comparatively low cost.

With these and other objects in view as will become more apparent as the description proceeds, the invention consists of certain novel features of construction, combination and arrangement of parts as will be hereinafter more fully described and claimed.

In the drawing:

Figure 1 is a vertical sectional view partly in elevation, illustrating the padlock constructed in accordance with my invention.

Fig. 2 is a longitudinal sectional view taken on the line 2—2 of Fig. 1,

Fig. 3 is a fragmentary sectional view

taken on the line 3—3 of Fig. 1, illustrating the barrel in unlocked position.

Fig. 4 is a longitudinal sectional view taken on the line 4—4 of Fig. 1, illustrating the means for connecting the barrel to one end of the shackle,

Fig. 5 is a perspective view of a sleeve located within the locking barrel,

Fig. 6 is a fragmentary perspective view of one end of the locking barrel,

Fig. 7 is a detail perspective view of one end of the shackle.

Referring in detail to the drawing, the numeral 1 indicates a shackle which is in the formation of a link providing an enlarged curved portion 2, which forms a space 3 for receiving the member which is to be locked. The ends of the shackle 1 are relatively spaced to form an entrance 4 to the space 3. One end of the shackle 1 is so bent as to form a straight portion 5, which has a plurality of recesses in which are slidably mounted pins 6, which are normally urged out of the recesses under the influence of coiled springs 7. A sleeve 8 of cylindrical formation is slidably mounted upon the straight end 5 of the shackle 1 and has a series of vertically arranged openings 9 which are adapted to receive the pins 6. The sleeve 8 is provided with a vertically extending slot 10 opening outwardly through the bottom end thereof and is adapted to receive a lug 11 formed upon the straight end 5 of the shackle 1 when the device is being moved to an unlocked position, which will be hereinafter more fully described. A projection 11' is formed upon the lower end of the sleeve adjacent the slot 10 and is adapted to engage the lug 11 for limiting the movement of the sleeve upon the straight end 5 of the shackle 1 in one direction.

Surrounding the sleeve 8 is a cylindrical locking barrel 12 having a series of vertically arranged apertures 13, which are adapted to register with the apertures 9 of the sleeve 8 and adapted to normally receive the outer ends of the pins 6 for locking the barrel against rotation upon the straight end 5 of the shackle 1. An offset portion 14 is formed upon the barrel 12 and has mounted therein a key plug 15 having the usual key slot 16 for slidably receiving a key 17. Mounted within the key plug 15 and the openings 13 of the locking barrel 12 are a series of pins 18, engaging balls which are adapted to be engaged by the shank of the

key 17 when inserted within the slot 16 which causes the pin 18 to move the pins 6 rearwardly within the recesses of the straight end 5 of the shackle 1 against the tension of the springs 7. The pins 18 move the pins 6 within the recesses of the shackle sufficiently enough to permit the pins 6 to engage the apertures of the sleeve 8, thus freeing the sleeve and locking barrel 12 upon the shackle so that the same may be rotated thereon.

The end 19 of the shackle 1 has formed thereon an extension 20 that has formed thereon an elliptical shaped plate 21. The upper end of the locking barrel 12 has an inwardly directed flange 22, which has an elliptical shaped opening 23 adapted to receive the elliptical plate 21 when the locking barrel 12 and the sleeve is moved upwardly upon the straight portion 5 of the shackle 1 and by turning the barrel and sleeve one-quarter of a turn to the left the elliptical opening 23 is arranged at right angles to the elliptical plate 21 thus locking the barrel 12 to the end 19 of the shackle, whereby the space 4 is closed preventing any member which may be located within the space 3 of the shackle from being withdrawn therefrom.

In operation, when desiring to unlock the aforescribed padlock, the key 17 is inserted in the slot 16 and as the notches upon the shank of the key engage the pins 18, moves the pins in the direction of the pins 6 and as the pins 18 move, the pins 6 are compelled to move against the tension of the springs 7, thus moving the pins 6 out of the apertures 9 of the sleeve 8, freeing the sleeve 8 and the locking barrel 12 upon the straight end 5 of the shackle. By turning the locking barrel 12 to the right, the elliptical opening 23 is brought into alignment with the elliptical shaped plate 21. The sleeve 8 is compelled to turn with the locking barrel 12 owing to the pins 18 extending into the apertures 9 of the sleeve, caused by the notches formed upon the shank of the key 17. As the barrel and sleeve rotate upon the shackle, the slot 10 within the sleeve 8 moves in alignment with the lug 11 upon the shackle, which permits the sleeve and barrel to move downwardly upon the straight portion 5 of the shackle opening the space 4, so that a member positioned within the space 3 of the shackle may be withdrawn therefrom or the member may be inserted through the passage 4 to the space 3.

When desiring to lock the shackle or close the space 4, the barrel 12 is moved upwardly accompanied with the sleeve 8, owing to the fact that the sleeve 8 is locked to the barrel by the pins 18 until the elliptical shaped plate 21 is received within the elliptical opening 23 of the barrel 12. The barrel 12 is then turned to the right accompanied with

the sleeve 8 arranging the elliptical opening 23 at right angles to the elliptical plate 21, thus forming a connection between the end 19 of the shackle and the barrel. As the barrel 12 is turned to the left, the sleeve 8 rotates therewith until the extension 11 engages the lug 11' upon the shackle, which limits the movement of the barrel 12 and the sleeve 8 to the left and simultaneously positioning the apertures 9 of the sleeve and the apertures of the enlargement 14 and slot of the straight portion 5 of the shackle 1 in alignment with each other so that when the key 17 is withdrawn from the slot 16, the pins 6 pass through the apertures 9 of the sleeve and into the apertures of the enlargement 14 of the barrel, thus locking the barrel and sleeve against rotation upon the shackle.

While I have shown and described the preferred embodiment of my invention, it will be understood that minor changes in construction, combination and arrangement of parts may be made without departing from the spirit and scope of the invention as claimed.

What is claimed is:

1. A padlock comprising a shackle having relatively spaced ends, a member carried by one end of the shackle and adapted to move in engagement with the other end of the shackle to close the space occurring between the ends of the shackle, means for locking the member to the second mentioned end of the shackle, and means for locking the member against movement.

2. A padlock comprising a shackle having relatively spaced ends, a barrel mounted upon one end of the shackle, locking plate carried by the other end of the shackle, said barrel having an opening for receiving the locking plate and adapted to be arranged at right angles to the locking plate for holding the barrel into engagement with the end of the shackle having the locking plate thereon, and means for locking the barrel against movement.

3. A padlock comprising a shackle having relatively spaced ends, a barrel slidable upon one end of the shackle and adapted to be moved in engagement with the other end of the shackle, pins carried by the first mentioned end of the shackle and adapted to lock the barrel against movement upon the shackle, and means for unlocking the barrel from the shackle.

4. A padlock comprising a shackle having relatively spaced ends, spring pressed pins carried by one end of the shackle, a sleeve carried by the last mentioned end of the shackle, and having apertures to receive said pins, a barrel surrounding said sleeve and having apertures to receive the pins, said barrel and said sleeve adapted to move into engagement with the other end

of the shackle, and means for urging the pins through the apertures when the barrel and sleeve are in the last mentioned position, and means for disengaging the pins 5 from the apertures of the barrel and sleeve.

5. A padlock comprising a shackle having relatively spaced ends, a sleeve mounted upon one end of the shackle, a barrel surrounding said sleeve, said barrel and 10 sleeve having alining apertures, said shackle having recesses, spring pressed pins mounted within said recesses and adapted to extend through the alining apertures of the sleeve and barrel when said sleeve and barrel 15 are moved in engagement with the other end of the shackle to close the space occurring between the ends of the shackle, and means for disengaging the pins from the apertures to free the barrel and sleeve upon the 20 shackle.

6. A padlock comprising a shackle having relative spaced ends, a sleeve surrounding one end of the padlock, a barrel surrounding the sleeve, the last mentioned end 25 of the shackle having recesses, said barrel and sleeve having vertically arranged alining apertures adapted to aline with the recesses of the shackle, spring pressed pins adapted to extend through the apertures of 30 the sleeve and barrel and mounted within the recesses, said barrel and sleeve adapted

to be moved in engagement with the other end of the shackle, and simultaneously receiving the sliding pins in the apertures thereof, and means carried by the barrel 35 and controlled by a key for disengaging the pins from the apertures of the barrel and sleeve.

7. A padlock comprising a shackle having relatively spaced ends, a sleeve surrounding one end of the shackle, a barrel surrounding the sleeve, said last mentioned end of the shackle having recesses, spring pressed pins located within the recesses, said barrel and sleeve adapted to be moved in 40 engagement with the other end of the shackle, and having alining apertures adapted to receive spring pressed pins, an enlarged portion formed on the barrel, pins 45 slidably mounted within the enlarged portion and adapted to move the first mentioned pins out of engagement with the apertures of the sleeve and barrel upon the insertion of a key within said enlarged portion.

In testimony whereof I affix my signature in presence of two witnesses.

JOHN S. RUDZINSKI.
